F. G. ADAMS.
CARBURETER.

1,242,630.

Patented Oct. 9, 1917.

UNITED STATES PATENT OFFICE.

FRED G. ADAMS, OF ROSCOE, MONTANA.

CARBURETER.

1,242,630.

Specification of Letters Patent.

Patented Oct. 9, 1917.

Application filed May 10, 1916. Serial No. 98,721.

To all whom it may concern:

Be it known that I, FRED G. ADAMS, a citizen of the United States, and a resident of Roscoe, in the county of Carbon and State of Montana, have invented an Improvement in Carbureters, of which the following is a specification.

This invention is an improvement in combustion engines and has particular reference 10 to a novel construction in a carbureter.

An object of the invention is to provide a construction wherein gasoline or other oils and water may be thoroughly mixed and supplied to the manifold of an engine, and 15 to this end, the invention includes upper and lower mixing chambers, the latter of which has mounted therein a plurality of mixing devices in the form of partitions constructed in a novel manner and having openings 20 therein through which the mixture passes under control of valves actuated at the will of the operator to regulate the amount of mixture passing through said openings. The upper mixing chamber has also mounted 25 therein a series of stationary and movable baffle members arranged in a novel manner.

The inventive idea involved is capable of receiving a variety of mechanical expressions, one of which, for the purpose of illustrating the invention, is shown in the accompanying drawing, in which—

Figure 1 is a vertical sectional view of the carbureter constructed in accordance with the invention.

Fig. 2 is a diagrammatic view of the mixing devices in the lower mixing chamber.

Fig. 3 is a transverse section on the line 3—3 of Fig. 1.

Fig. 4 is a fragmentary perspective view 40 of the means for operating the valves controlling the openings through the partitions in the lower mixing chamber.

There is illustrated in the drawing what is now believed to be a preferred form of the 45 invention in which the same includes a base 5 upon which is mounted a lower mixing chamber 6 of ordinary construction having upper and lower restricted neck portions 7 and 8, respectively, the latter being secured 50 to the base 5 in any preferred manner. Also supported upon the base 5 are the gasoline and water tanks 9 and 10 having the usual floats 11 mounted therein. Connected to the tanks 9 and 10 by means of pipes 12 and 13 55 are the needle valves 14 and 15 which project through the base 5 and into the restricted

portion 8 of the mixing chamber 6, said valves being employed for the purpose of controlling the inflow of gasoline or other oil and water into said chamber. Air enters 60 the neck 8 through the pipe 8.

A fixed casing 16 having a bottom 17 is mounted interiorly of the mixing chamber 6 in the center thereof and in alinement with the restricted portions 7 and 8, the bottom 65 17 of said casing being adapted to deflect and assist in mixing the oil and water in the tanks 9 and 10. At intervals in the space between the wall of the chamber 6 and the casing 16 there are mounted in superposed 70 relation, a series of separate partitions 18 adapted to effectively obstruct and prevent the quick passage of the mixture through the mixing chamber. The bottom partitions are provided with openings 19 through which 75 the mixture is allowed to pass, at certain times, into the space between said lower partitions and the next partitions above. Each of the lower partitions 18 is provided contiguous to the opening 19 therein with a 80 baffle plate 20 which is adapted to cause the mixture to rise upwardly, and strike against the bottom of the next superposed partition. Each of the other partitions 18 is provided with a similar opening 19 and baffle plate 85 20. The partitions 18 above the lowermost one are also provided with downwardly extending baffle portions 21 forming continuations of the baffle plates 20 and projecting down as far as the level of the next lower 90 partition 18. Each of the said partitions is also provided with a depending baffle plate 22 arranged adjacent the baffle plates 20 and extending at substantially right angles thereto, the same being adapted to deflect the mixture downwardly as shown by the direction 95 of the arrows, after which said mixture again rises and passes through the openings 19 in the next superposed partitions. Each of these openings 19 is controlled by a flap 100 valve 23 pivoted at 24 to the downwardly extending baffle portion 21 of the adjacent partition 18. The flap valves 23 are preferably slightly curved, as shown in Figs. 1 and 4, and are arranged concentrically about the inner fixed casing 16, the pivots 24 for said valve extending radially with reference to the vertical axis of said inner casing, as clearly shown in Fig. 4. A portion 25 of each valve 23 projects slightly beyond its pivot 24 and is secured to one end of an arm 105 26 projecting through an opening 27 formed

in the casing 16, the other end of said arm being connected to one of a number of rods 28 forming a portion of a vertically adjustable frame, said rods being secured to a ring 5 member 29 forming the base of said frame which is arranged interiorly of the casing 16.

Means for adjusting the above-mentioned frame are provided and preferably include rods 30 extending transversely of the ring 10 member 29 and having connected thereto at each end one end of a link 31 which together with the link 32 and operating arm 33 forms a toggle. The other end of the link 31 together with the adjacent end of 15 the link 32 is pivoted upon a rod 34 mounted in the arm 33 while the other end of the link 32 is mounted upon a stationary rod 35. The arm 33 is under the control of the operator and it will be seen that by pushing 20 the arm inwardly the links 31 and 32 of the toggle will be straightened and cause the rods 28 and ring member 29 of the frame to be lowered into the casing 16 whereupon the arms 26 will swing the valves 23 about 25 their pivots 24 and raise said valves so that the mixture will be permitted to pass through the openings 19 in the different partitions 18 and, owing to the arrangement of the different baffle members, be caused to 30 take the passage indicated by the arrows.

The upper restricted portion 7 of the lower chamber 6 has mounted therein a throttle valve 36 the pivot for which is controlled by a lever 37 connected to an arm 38 35 arranged in parallel relation and connected to the arm 33 so that said arms will be simultaneously operated.

The top of the restricted portion 7 is provided with a flange 39 upon which is mounted the upper mixing chamber 40 which is preferably of a cylindrical formation. The inner wall of the chamber 40 has projecting therefrom, in an upwardly direction and toward the center thereof, a plurality of stationary baffle plates 41. A vertical partition 42 is centrally arranged in the chamber 40 and has pivoted thereto at oppositely disposed points a plurality of valves 43 which coöperate with the stationary baffle plates 45 41 to cause the mixture coming from the lower mixing chamber to assume a tortuous passage, as indicated by the arrows, through the said chamber 40. Should the pressure of the mixture past the throttle 50 valve 36, when open, be insufficient to maintain the valves 43 opened or should the throttle valve 36 be closed, said valves 43 will automatically lower and rest upon the ends of the baffle plates 41 thus cutting off 55 the flow of the mixture through the mixing chamber 40. The upper end of this chamber 40 is provided with an outlet opening 44 and is connected to the engine manifold 45.

What is claimed is:

1. A carbureter including upper and lower mixing chambers having a connection therebetween, a valve for controlling the passage of mixture from one chamber through said connection to the other chamber, a fixed casing mounted in said lower mixing chamber, a plurality of superposed partitions arranged exteriorly of said inner casing and having openings therein, baffle plates extending upwardly from certain of 70 said partitions adjacent said openings, other baffle plates depending from said partitions and arranged at substantially right angles to the first-named baffle plates, a valve arranged concentrically of said inner casing 75 for controlling the passage of mixture through each of the openings in said partitions, a pivot for said valve extending radially relative to the vertical axis of said inner casing, a vertically adjustable frame mounted in said inner casing, connections between said frame and said valves for opening and closing the latter when said frame is adjusted, and toggle mechanism connected to said frame and to said throttle 90 valve for operating all of the valves simultaneously.

2. A carbureter comprising upper and lower mixing chambers having a connection therebetween, a throttle valve for controlling the passage of mixture from one chamber to another through said connection, a casing mounted in said lower mixing chamber, partitions mounted in said chamber exteriorly of said casing and having openings therein, baffle plates arranged between said partitions, flap valves for controlling the openings in said partitions, and means for simultaneously operating said throttle and flap valves.

3. A carbureter comprising upper and lower mixing chambers having a connection therebetween, a throttle valve for controlling the passage of mixture from one chamber to another through said connection, a casing mounted in said lower mixing chamber, partitions mounted in said chamber exteriorly of said casing and having openings therein, baffle plates arranged between said partitions, flap valves for controlling the openings in said partitions, and means including a vertically adjustable frame connected to said flap valves for simultaneously operating the same and said throttle valve.

4. A carbureter comprising upper and lower mixing chambers having a connection therebetween, a throttle valve for controlling the passage of mixture from one chamber to another through said connection, a casing mounted in said lower mixing chamber, partitions mounted in said chamber exteriorly of said casing and having opening therein, baffle plates arranged between said parti-

tions, flap valves for controlling the openings in said partitions, means for simultaneously operating said throttle and flap valves, a series of stationary baffle plates mounted in 5 said upper mixing chamber, and valves pivoted in said chamber for automatically controlling the passage of mixture past said stationary baffle plates.

5. A carbureter including a mixing chamber, a casing mounted therein, a plurality of superposed partitions also mounted in said chamber exteriorly of said casing and having openings therein, baffle members extending upwardly and depending from certain of 10 said partitions, means for controlling the passage of a mixture through the openings in said partitions, and vertically adjustable means mounted interiorly of said inner casing for operating said last-named means to 15 open and close said openings.

6. A carbureter including a mixing chamber, a casing mounted therein, a plurality of superposed partitions also mounted in said chamber exteriorly of said casing and having 20 openings therein, baffle members extending upwardly and depending from certain of said partitions, means for controlling the passage of a mixture through the openings in said partitions, vertically adjustable 25 means mounted interiorly of said inner casing for operating said last-named means to open and close said openings, and a toggle mechanism for operating said vertically adjustable means.

30 7. A carbureter including a mixing chamber, an inner casing mounted therein, baffle devices also mounted in said chamber exteriorly of said inner casing, valves arranged concentrically about said inner casing for controlling the passage of a mixture past 35 said baffle devices, and means adjustable longitudinally of the said inner casing for operating said valves.

8. A carbureter including a mixing chamber, an inner casing mounted therein, baffle 45 devices also mounted in said chamber exteriorly of said inner casing, valves arranged concentrically about said inner casing for controlling the passage of a mixture past 50 said baffle devices, means adjustable longitudinally of the said inner casing for operating said valves, and a toggle mechanism for actuating said longitudinally adjustable means.

9. A carbureter including a mixing chamber, an inner casing mounted therein, baffle devices also mounted in said chamber exteriorly of said inner casing, valves arranged concentrically about said inner casing for controlling the passage of a mixture past 55 60 said baffle devices, means adjustable longitudinally of the said inner casing for operating said valves, a second mixing chamber connected to the first-named chamber, baffle devices mounted in said second chamber, and means for controlling the passage 65 of mixture between said chambers.

10. A carbureter including a mixing chamber, an inner casing mounted therein, baffle devices also mounted in said chamber 70 exteriorly of said inner casing, valves arranged concentrically about said inner casing for controlling the passage of a mixture past said baffle devices, means adjustable longitudinally of the said inner casing for operating 75 said valves, a second mixing chamber connected to the first-named chamber, baffle devices mounted in said second chamber, and means operated simultaneously with said longitudinally adjustable means for 80 controlling the passage of a mixture between said mixing chambers.
